UNITED STATES PATENT OFFICE.

JAMES V. STANSELL, OF EVA, ALABAMA.

FENDER FOR PLOWS.

1,258,492.

Specification of Letters Patent.

Patented Mar. 5, 1918.

Application filed October 12, 1917. Serial No. 196,220.

To all whom it may concern:

Be it known that I, JAMES V. STANSELL, a citizen of the United States, residing at Eva, in the county of Morgan and State of Alabama, have invented new and useful Improvements in Fenders for Plows, of which the following is a specification.

This invention relates to fenders for plows that are used for cultivating cotton and the like.

The invention has for its object to produce a fender of simple and improved construction which will yield to pressure in an upward direction so that it may pass over obstructions such as stones and grubs without injury to the parts thereof.

A further object of the invention is to simplify and improve the construction of the frame wherein the fender is mounted and whereby it is connected with the plow.

With these and other ends in view which will readily appear as the nature of the invention is better understood, the same consists in the improved construction, arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing:—

Figure 1 is a view in side elevation showing a plow to which the improved fender has been attached.

Fig. 2 is a perspective view showing the fender and its supporting frame detached from the plow.

Fig. 3 is a plan view of a blank from which the fender frame may be manufactured.

Corresponding parts in the several figures are denoted by like characters of reference.

The blank illustrated in Fig. 3 consists of a plate of sheet metal 16 provided at its lower end with a cross piece 18. The upper end of the sheet 16 has a notch 19. To convert the blank into the desired frame structure the upper end portion thereof is bent on the lines 21—22 to form an offset 23 which is provided with an aperture 24, said offset being at right angles to the body por-

tion of the sheet 16 and the notched portion 25 being at right angles to the said offset and disposed in parallel relation to the body portion 16. The cross piece 18 is bent to 60 form a sleeve 30 as best seen in Fig. 2.

17 designates an arm or brace which is provided at one end thereof with a notch 20. The arm is also bent on the lines 26—27 to produce an offset 28. The arm 17 is connected with the shank or body portion 16 of the frame by means of a bolt or pivot member 15.

B designates a stem or shank having a portion 31 of rectangular cross section, said 70 portion being guided in the sleeve 30, said stem having another portion 32 of circular cross section which is guided through the aperture 24 in the offset portion 23 of the frame. At the juncture of the circular portion 32 and the rectangular portion 31 is formed a shoulder 33 on which abuts the lower end of a spring 34 which is coiled about the circular portion 32 and the upper end of which abuts on the offset portion 23 80 of the frame, thereby projecting the stem B in a downward direction, the extent of the downward movement being limited by a pin or stop member 25 extending through the stem above the offset 23. The lower end 85 of the stem carries a fender disk 36 which is mounted for rotation on a pin or pivot member 37.

38 designates the beam of a plow, the same having a stock 39 connected therewith 90 by means of bolts 40—41. By loosening the nuts on the bolts the portion of the frame having the notch 19, and the end of the arm or brace 17 having the notch 20 may be engaged therewith without detaching the bolts, 95 the device being firmly secured in position by simply retightening the nuts. The offset portions of the frame structure will support the fender at the requisite distance from the side of the plow, and the rectangular portion of the stem 31 will prevent the rotation

of the same, thereby serving to maintain the fender disk in proper position to protect the plants from dirt thrown by the plow when the latter is used for cultivating purposes. 105 The device may be reversed from right to left for attachment to either side of the plow by simply swinging the arm 17 from one side of the main frame and the other as indicated by the dotted lines in Fig. 2. The 110 improved device is not only of extremely simple construction but it is found efficient

in operation and of such a nature as to yield to upward pressure, thereby permitting the fender to pass over obstructions without injury.

5. What is claimed is:—

1. A fender frame comprising a body portion having a notch at its upper end, said body portion being so bent that the notched portion will be supported in spaced and 10 parallel relation to the body, and the offset portion of the body being provided with an aperture, the lower end of the body having a rectangular sleeve formed by bending laterally extending portions thereof, and an 15 arm pivotally connected with the body portion and having near its free end an offset portion provided with a notch.

2. A fender frame comprising a body portion having a laterally extending pivoted 20 arm, said body portion having a notch at its upper end and said arm having a notch at its outer end, said body portion and arm being so bent that the notched portions will be in spaced and parallel relation to the body portion, and the offset portion of the body being provided with an aperture, the lower end of the body having a rectangular sleeve formed by bending laterally extending 25 portions thereof, in combination with a fender

carrying stem having a rectangular portion 30 guided in the sleeve and a round portion guided in the aperture of the notched offset portion of the body member.

3. A fender frame comprising a body portion having a laterally extending pivoted 35 arm, said body portion having a notch at its upper end and said arm having a notch at its outer end, said body portion and arm being so bent that the notched portions will be in spaced and parallel relation to the 40 body portion, and the offset portion of the body being provided with an aperture, the lower end of the body having a rectangular sleeve formed by bending laterally extending 45 portions thereof, in combination with a fender carrying stem having a rectangular portion guided in the sleeve and a round portion guided in the aperture of the notched offset portion of the body member, a spring coiled about the circular portion of the stem 50 and abutting terminally on the rectangular portion of the stem and on the offset portion of the body member, and a stop member to limit the downward movement of the fender stem under the tension of the spring. 55

In testimony whereof I affix my signature.

JAMES V. STANSELL.
